CLAIM

The ornamental design for an adapter as shown and described.

DESCRIPTION

FIG. 1 is top perspective view of an adapter taken from the front, showing my design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a top perspective view thereof, taken from the rear; and,

FIG. 9 is a bottom perspective view thereof, taken from the front.

The broken lines in the drawings depict portions of the design that form no part of the claim.
